UNITED STATES PATENT OFFICE.

ENOS GOBLE BUDD, OF BUDD'S LAKE, NEW JERSEY.

IMPROVEMENT IN SAWING-MACHINES.

Specification forming part of Letters Patent No. 130,840, dated August 27, 1872.

Specification describing an Improved Sawing-Machine, invented by ENOS GOBLE BUDD, of Budd's Lake, in the county of Morris and State of New Jersey.

My invention relates, first, to a frame for supporting and guiding the saw and its operating mechanism, which is to rest upon and be secured to the log to be sawed; and, secondly, to the arrangement of the said mechanism, the same consisting, in the main, of a novel application of a "lazy-tongs," as herein-after described.

In the drawing I have represented my improved machine attached to and operating (or ready for operation) upon a log.

The frame A is formed of two vertical iron standards, united by a cross-bar at the top, and provided with feet or sharp ends, which enter the log L. The frame is firmly braced by two sets of rods, d^s and e^s, which have hooks for taking into the log at d d^s. The saw I is secured at each end in clamps H^s i^s, which are formed on or attached to the vertical bars G^s passing through the sockets F on the ends of the bar E. Said bar E passes through vertical slots, at c e, in the frame A. The two sets of "lazy-tongs" B B are connected at their outer ends with the bar E by pins or bolts b b^s working in slots B^s, and at their inner ends to the bars or levers C^s C^s, pivoted respectively, at a^s and a^s to a central portion of the vertical frame. To impart an oscillating movement to levers C^s C^s I employ a balance-wheel, D, having a handle, K, and mounted on a crank-shaft, h, which passes through the beam D^s. This beam is connected with the ends of the lever C^s by bars C.

The operation is as follows: To prepare the frame to be set upon a log the saw is secured firmly by tightening the screws g³ g³. The frame is then hoisted into position, and the brace-rods properly arranged and hooked into

the log. The screws g³ being loosened so as to allow vertical play to the guide-bars or handles G^s, the saw is ready to operate. Upon turning the wheel D the beam D^s is oscillated by the crank-shaft h, and a similar movement necessarily communicated to the corresponding beam or lever C^s. This will have the effect to alternately contract and extend the respective "lazy-tongs," one being always in the act of opening as the other is closing, and, inasmuch as they are connected with the saw, a reciprocating movement of the latter is obtained.

It will be observed that the lever C^s can act on the lever C^s only through the medium of the first sets of cross-bars of the tongs. The gravity of the saw insures its descent and efficient action on the log when reciprocated as desired.

This machine is light and portable, easily set up or changed in position, comparatively inexpensive in construction, and may be operated by one man.

What I claim as new is—

1. In combination with the frame A for supporting and carrying the operative mechanism of a saw, the brace and hook rods d^s d^s and e^s e^s, all as shown and described, whereby said frame is adapted to be secured to a log, as specified.
2. The combination of the two sets of "lazy-tongs" B B with the bar E, sockets F, saw I, guide-bars G^s, frame A, as set forth.
3. The combination of the two sets of "lazy-tongs" B B, bar E, sockets f f, guide-bars G^s, saw I, frame A, beams or levers C^s C^s and D^s, connecting-bars C, crank-shaft h, and wheel D, as specified.

ENOS GOBLE BUDD.
